PHOTOGRAPHIC FLASH LAMP

George H. Kress, Endicott, N. Y.

Application September 6, 1956, Serial No. 42,856

Term of patent 14 years

(Cl. D61—1)

FIG. 1

FIG. 3

Fig. 1 is a side elevational view of the photographic flash lamp, showing my new design;

Fig. 2 is a front elevational view thereof; and

Fig. 3 is a rear elevational view of the same.

I claim:

The ornamental design for a photographic flash lamp, substantially as shown.
